CLAIM

The ornamental design for a plant stand as shown and described.

DESCRIPTION

FIG. 1 is a top, front, right side perspective view of a plant stand, showing the claimed design;

FIG. 2 is a front elevation view of the claimed design, the rear elevation view being a mirror image thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a bottom, front, left side perspective view thereof; and,

FIG. 8 is a front view thereof with another plant stand to form a heart-shaped appearance in a state of use.

The dashed broken lines in the drawing depict portions of the plant stand that form no part of the claimed design.

The dashed broken lines of the other plant stand at right side in FIG. 8 depict environment that forms no part of the claimed design.
